Primary Examiner — Wan Laymon

CLAIM

The ornamental design for a surgical fastener cartridge, as shown and described.

DESCRIPTION

The Applicant of the present application owns the following U.S. Design Patent Applications that were filed on Jun. 24, 2016 and which are each herein incorporated by reference in their respective entireties:

U.S. Design patent application Ser. No. 29/569,218, entitled Surgical Fastener, now U.S. Design Pat. No. D826,405; U.S. Design patent application Ser. No. 29/569,227, entitled Surgical Fastener, now U.S. Design Pat. No. D822,206; and U.S. Design patent application Ser. No. 29/569,259, entitled Surgical Fastener Cartridge.

FIG. 1 is a perspective view of a surgical fastener cartridge. FIG. 2 is a top plan view of the surgical fastener cartridge of FIG. 1.

FIG. 3 is a bottom plan view of the surgical fastener cartridge of FIG. 1.

FIG. 4 is a front elevation view of the surgical fastener cartridge of FIG. 1.

FIG. 5 is an enlarged left elevation view of the surgical fastener cartridge of FIG. 1.

FIG. 6 is an enlarged right elevation view of the surgical fastener cartridge of FIG. 1; and,

FIG. 7 is another enlarged perspective view of the surgical fastener cartridge of FIG. 1.

1 Claim, 5 Drawing Sheets
